UNITED STATES PATENT OFFICE.

EDWARD H. CANON, OF MCKEESPORT, PENNSYLVANIA.

LOCK.

Application filed July 3, 1926. Serial No. 120,408.

This invention relates to locking devices and more particularly to that type of locking device especially adapted for use in connection with sliding sash windows for limiting the extent to which the sashes can be opened.

An object of this invention is to provide an improved device of the type set forth of such construction and arrangement that a single lock will be sufficient to prevent the opening of both the upper and lower window sashes beyond a predetermined extent.

A further object is to provide a window lock of the type set forth of simple and rugged construction which will be cheap to manufacture, reliable in operation and easily applied to any window of the sliding sash type, and which will not impede nor hinder the normal operation of the window sash when the lock is rendered ineffective.

These and other objects which will be apparent to those skilled in this particular art are attained by means of the invention illustrated in the accompanying drawings, in which Figure 1 is a sectional view through a window provided with one form of this invention and illustrating the same in its operative position. Fig. 2 is a sectional view along the line 2—2 of Fig. 1. Fig. 3 is a cross section on the line 3—3 of Fig. 1, illustrating the present invention in operative locking position and Fig. 4 is a similar view showing the window unlocked. Fig. 5 is a detail view of one form of window sash adapted to be used with the illustrated embodiment of this invention and Fig. 6 is a sectional view thereof. Fig. 7 is a view similar to Fig. 5 of a somewhat different form of window sash and Fig. 8 is a sectional view thereof.

The particular embodiment of this invention which has been chosen for the purposes of illustration is shown applied to an ordinary double sash window of the sliding type which is formed by a window frame 10 provided with an upper sash 11 slidably mounted in the usual slideways 12 and a lower sash 13 is mounted in slideways 14 and cooperating with the upper sash 11 in the usual manner to close the window. The inner side of the slideway 14 is formed by the usual strip 15.

As illustrated, the lock forming the present invention is in the form of a stop or block 16 hinged to one side of the frame 10

in a slot 17 formed in the strip 15 for the purpose of receiving the block 16 so that the latter may be swung into such position as to extend across the slideway 14 for the lower sash. Obviously, when in this position the block forms a positive stop which definitely limits the extent of upward movement which can be given to the lower window sash. The stop block has a groove 18 formed therein for the reception of the usual counterbalance chain 19 connected to the lower sash.

The locking block 16 is so arranged that the locking mechanism therefor forms a lock for the upper sash. The arrangement is such that the upper sash may be locked thereby in any predetermined position or may be confined to a limited movement of predetermined extent, so that the single device serves as a locking medium for both sashes. As illustrated, this mechanism is formed by a key operated locking bolt 20 slidably mounted in the block 16 and adapted to be moved into a cooperating locking recess formed in the adjacent surface of the upper window sash and which may be in the form either of the continuous groove 21 illustrated in Figs. 5 and 6 or the spaced locking recesses 22 shown in Figs. 7 and 8. It will be apparent that when the locking bolt 20 is in cooperating relation with the locking groove 21 or one of the locking recesses 22, that the block 16 is positively locked in operative position so as to limit the opening of the lower sash and at the same time the locking bolt prevents the upper sash being opened more than its allotted extent.

In order to relieve the hinge supporting the block 16 from undue strains the block is provided with a rugged strain bearing lug 23 adapted to be received within a recess 24 formed in the adjacent portion of the window frame 10. It will be apparent that this recess may be reinforced by a slotted plate 24' and that any jarring to which the locking block is subjected will thus be borne by the lug 23 and the supporting hinge will be relieved of all or a portion of such strains.

When it is desired to open the window to its fullest extent the lock block 16 can be unlocked by withdrawing the key operated sliding locking bolt 20 and then the block 16 may be swung outwardly to the position

shown in Fig. 4, in which it in no way impedes or hampers the movement of either sash.

Ordinarily the form of upper sash having a groove 21, as illustrated in Figs. 1 to 6, will be preferred as this form permits the upper sash of the window to be opened or shifted within its limits of movement without the necessity of unlocking or withdrawing the locking bolt 20.

It will, of course, be apparent that the groove 21 will preferably be formed in a metal plate 21' which is set into the sash so that its surface is flush with the sash surface; and that similar plates may be employed in connection with the recesses 22. The plate 24' may also be so formed that it reinforces or supports the ends of the sash parting strip 25, which as shown in Fig. 1, is formed in two parts so that the lock may perform the double function of locking both sashes.

Although I have described a specific arrangement it will be apparent that various changes, additions, omissions and substitutions can be made therein without depart-

ing from the spirit of this invention or the scope of the appended claims.

What I claim as new and desire to secure by Letters Patent is:

1. The combination with a window of a block hinged to the frame thereof and movable into the pathway of one sash so as to limit the opening thereof, means on said block for limiting the opening of the other sash and means for relieving said hinge of jarring strains produced by said sashes striking the block.

2. The combination with a window of a block hinged to the frame thereof and movable into the pathway of one sash so as to limit the opening thereof, means on said block for limiting the opening of the other sash, a recess in the frame of said window and a pin in said block receivable within said recess for relieving said hinge of the strains caused by said sashes striking said block.

In testimony whereof, I have hereunto subscribed my name this 2nd day of July, 1926.

EDWARD H. CANON.
